UNITED STATES PATENT OFFICE.

ALEXANDER ALFRED GERICKE, OF DETROIT, MICHIGAN.

ADJUSTABLE DIE.

1,348,403.

Specification of Letters Patent.

Patented Aug. 3, 1920.

Application filed September 19, 1919. Serial No. 324,761.

To all whom it may concern:

Be it known that I, ALEXANDER A. GERICKE, a citizen of the United States, residing at Detroit, in the county of Wayne and 5 State of Michigan, have invented certain new and useful Improvements in Adjustable Dies, of which the following is a specification.

This invention relates to dies for cutting 10 threads upon rods or tubes and has for its object the provision of a die which may be readily adjusted to the diameter of the rod or tube which is to be threaded. The invention also seeks to provide a die which 15 will be simple in construction and in which the parts will be compactly arranged and devoid of complicated structure or operation. The invention is illustrated in the accompanying drawings and will be herein- 20 after fully described, the novel features being subsequently particularly pointed out in the appended claims.

In the drawings—

Figure 1 is a perspective view of a die 25 constructed in accordance with my invention and showing it assembled for use;

Fig. 2 is a longitudinal section taken on the line 2—2 of Fig. 1;

Fig. 3 is a transverse section taken on the 30 line 3—3 of Fig. 2;

Fig. 4 is a perspective view of one of the cutters.

In carrying out my invention, I employ a base or socket member consisting of an annular rim or collar 1 having a diaphragm 2 at one end. This diaphragm has a central opening 3 of a diameter sufficient to accommodate the maximum diameter of rod upon which the die may be used and extending 40 outwardly from the said central opening are a plurality of radially disposed notches or open-ended slots 4. The external surface of the rim or collar 1 may be smooth or may be knurled or otherwise treated but the interior surface of said collar is threaded, as shown at 5, to be engaged by the external threads 6 of a clamping member 7 which is preferably in the form of a circular disk or web having a central opening and provided 50 with a hub or circular projection 8 upon one face, the external periphery of the hub being knurled or otherwise treated, as shown at 9, whereby it may be firmly grasped by the hand of the operator. The central opening 55 through the hub portion of the clamping member is threaded for a purpose to be pres-

ently set forth but in the body portion of the clamping member the central opening is provided with a smooth wall, which is flared, as shown at 10, toward the inner end or face 60 of the body member whereby it is adapted to ride over the cutters and move the same radially of the base member so that they will be properly set to engage the work. The cutters 11 are substantially three-sided 65 blocks, two sides or ends 12 of the blocks being flat and disposed approximately on radii of the base member, while the third side is arcuate so as to conform to the arcuate surface of the chamber 10 in the clamping member and also inclined or tapered to correspond to the flare of the wall of said chamber. The apex or meeting corner of the flat ends or sides 12 of the cutter is cut away and dished, as shown at 13, sharp 70 threads or cutting surfaces 14 being formed upon the said dished face 13, as clearly shown. These cutting teeth or threads will be of the same pitch or size in all the cutters of a given set and when a pipe or rod is 75 threaded the set of cutters having the required pitch or size of thread will be placed within the base member of the die. The end faces of the cutter, as shown at 15 and 16, are flat and disposed in planes at a 80 right angle to the axis of the die, the larger face 15 setting against the inner surface of the web 2 and being constructed with a radial lug 17 to fit within the proper notch or slot 4 and slidably engage the same so as 85 to guide the cutter in its adjustment. The face 16 of the cutter is free of projections so that it may be engaged by the end wall of the chamber 10 and by the end of a locking screw or sleeve 18 which is threaded 90 through the hub member 7, as clearly shown in Fig. 2, the projecting end of the said locking sleeve or screw being knurled or otherwise treated, as shown at 19, whereby it may be firmly grasped by the operator.

It is thought the construction and arrangement of the several parts of the device having been thus set forth, the operation of the same will be readily understood from the accompanying drawings. The base member 105 is placed upon a table or other flat surface with the open end of the rim 1 uppermost. The proper cutters are then inserted in the base member with their projections or lugs 17 fitting within the respective slots 110 or notches 4 of the web 2, after which the clamping member 7 is inserted in the upper

end of the ring or collar 1 and engaged therewith. Any convenient form of gage rod may then be inserted between the cutters so that if the cutters be moved inwardly 5 to engage around the said rod they will be set to the diameter of the rod or pipe which is to be threaded. The clamping member is then rotated so that it will ride downwardly in the ring or collar 1 and 10 as it thus rides downwardly the central flared chamber thereof will engage the inclined outer surfaces of the cutters and effect a wedging engagement therewith so as to force them radially toward the center 15 of the die. When the cutters have been thus caused to bear against the gage rod the further rotation of the clamping body may cease and the gage rod be withdrawn. The locking sleeve 18 is then rotated so 20 that it will ride inwardly through the hub 8 and bring its inner end to bear upon the inner faces of the several cutters. When this locking sleeve has been turned home against the cutters it will effectually bind 25 them against the web 2 so that they will be locked in their adjusted positions and the die, therefore, set for use. The die may then be used in the usual manner and will cut the threads readily without any 30 liability of the cutters slipping while in use. Should it be necessary to adjust the dies before the threads are completely formed so as to deepen the previously made cut, the locking sleeve is slightly released 35 after which the adjusting body 7 is turned so as to move the cutters slightly inward after which the locking sleeve is again turned home.

My device is obviously simple in the construction and arrangement of its parts and a minimum number of parts is employed. The cutters can be quickly and easily adjusted to the diameter of the work and after being set for the desired work will 45 be firmly held so that they will not slip while in use.

The die can be held in any standard die-holder and can be operated manually or in a thread-cutting machine.

Having thus described the invention, what is claimed as new is:

1. A die comprising a base member, a

plurality of cutters fitted in the base member for movement radially thereof, an adjusting member fitted in the base member for movement longitudinally of the same and adapted to engage the dies and effect radial movement thereof, and means fitted in said adjusting member to lock the cutters in their set position. 60

2. A die comprising a socket member, cutters carried by the socket member, an adjusting disk fitted in the socket member and movable longitudinally thereof and having a central flared chamber to receive the cutters and effect radial movement thereof, and a locking member carried by the said adjusting member and arranged to engage the cutters and lock them in a set position. 70

3. A die comprising a socket member having a web across one end provided with a central opening, and a plurality of notches radiating from said opening, cutters housed within the socket member and provided with guides slidably engaging said notches, an adjusting member mounted in the socket member and engaging the cutters to effect radial movement thereof, and means carried by said adjusting member to lock the cutters in a set position. 80

4. A die comprising a socket member, a plurality of cutters fitted within the socket member for radial movement and having tapered outer surfaces, an adjusting disk rotatably fitted within the socket member and movable longitudinally thereof and provided with a central flared chamber to engage the outer tapered surfaces of the cutters whereby to effect radial movement 90 of the cutters, and means carried by said adjusting member to lock the cutters in a set position. 85

5. A die comprising a socket member, a plurality of cutters mounted therein for radial movement, an adjusting disk fitted in the socket member and movable longitudinally thereof to engage the cutters and effect radial movement of the same, and a locking screw fitted in the adjusting member 100 and adapted to bear against the cutters to lock them in a set position.

In testimony whereof I affix my signature.

ALEXANDER ALFRED GERICKE. [L. S.]
